HERBERT C. WILLIAMSON AND BUFORD M. STUBBLEFIELD, OF YOUNGSTOWN, OHIO,
ASSIGNORS TO THE YOUNGSTOWN SHEET AND TUBE COMPANY, OF YOUNGSTOWN,
OHIO, A CORPORATION OF OHIO.

GAS VALVE.

Application filed September 28, 1925. Serial No. 59,226.

The present invention relates to an improved form of valve for controlling the flow of gases from retorts, furnaces and the like and is particularly adapted for effecting the control of the gases passing from by-product coke furnaces to the collector main utilized in conjunction therewith and in which the gases from the different furnaces in the battery are collected and thence 5 conveyed from the furnace preparatory to distillation or other suitable treatment in accordance with the well known practice.

In the operation of such furnaces the gases in their passage therefrom deposit considerable quantities of carbon on the walls of the passages through which they flow and these deposits must be removed from time to time to maintain a free passage for the gases and to insure the proper operation 10 of the valve by which their flow is controlled, such removal being preferably effected by thoroughly flushing the interior of the valve body or casing with a suitable flushing liquid introduced thereinto by suitable spray nozzles or the like.

A principal object of our invention is to provide a valve for the purpose aforesaid so constructed as to afford a continuous liquid seal against the passage of the gases 15 when the valve is closed, the liquid forming the seal being derived from the flushing liquid utilized in freeing the interior of the valve casing from the carbon deposits and which is adapted to permit the flushing liquid, in excess of the quantity required to 20 form the seal, to continuously overflow into the collector main or other receptacle with which the valve is connected so that the said liquid is prevented from collecting in the 25 valve casing in undesirable quantities after it has performed its function of cleaning the carbon deposits from the interior thereof.

Our invention also contemplates a novel 30 arrangement of spray nozzles for spraying the interior of the valve casing and the valve with flushing liquid so as to effectively remove the deposits of carbon, as well as provision of a valve body of novel design 35 whereby the possibility of the flushing liquid overflowing into the ascension pipe and thence passing to the furnace in case for any reason it cannot escape past the valve

and into the collector main in the normal manner is minimized.

A further object of our invention is the provision of improved means for operating the valve from a point exterior of the valve casing with a maximum of convenience from a plurality of different points such as the 40 charging lorry, the collector main walk or the top of the furnace battery.

Our invention additionally includes other objects and novel features of design, construction and arrangement hereinafter more 45 specifically referred to or which will be apparent from the accompanying drawings forming a part hereof.

For the purpose of enabling those skilled in the art to understand and practice the 50 invention we have illustrated in the said drawings and will now proceed to describe, a preferred embodiment thereof installed in connection with one of the furnaces comprised in the battery of a by-product coke 55 furnace, only so much of the furnace proper and its well known auxiliaries being illustrated, however, as is necessary for an adequate comprehension of the invention.

In the said drawings, Fig. 1 is a central 60 vertical section through the valve, valve casing and ascension pipe with which the latter is connected, the collector main and certain parts adjacent thereto being indicated in dot and dash lines; Fig. 2 is a fragmentary top 65 plan view of the valve body and adjacent parts shown in Fig. 1; Fig. 3 is an end elevation of the valve body; Fig. 4 is a fragmentary enlarged section on line 4-4 in Fig. 2 looking in the direction of the arrows; Fig. 5 is a top plan view of the valve clapper removed from the casing and Fig. 6 a central vertical section through the valve clapper on a larger scale. Like symbols are 70 used to designate the same parts in the several figures.

As shown and in accordance with the usual practice the furnace may be provided with a collector main C which extends 75 across the tops of the several furnaces composing the battery and is carried on supports S in turn mounted on suitable framework S'. Each individual furnace in the battery is provided with a vertically disposed ascension pipe which is usually formed of independent sections P, P' connected by a flex- 80

ible or expansion joint J of any suitable construction. The lower end of the lower section P of the ascension pipe communicates with the furnace (not shown) so as to 5 receive the gases therefrom and conduct them upwardly while the upper end of the upper section P' may be turned horizontally and provided with a flange F for connection with a corresponding flange formed 10 at the adjacent end of the valve body hereinafter described. An opening O may be provided near the upper end of the ascension pipe to give access to the interior of the same for cleaning, under normal conditions of operation this opening being closed 15 by a cover O'.

The valve forming the subject of our invention is interposed between the end of the ascension pipe and the collector main 20 and as shown comprises a valve casing 1, generally cylindrical in horizontal section, from which extends a conduit 2 preferably formed integral with the casing proper and connecting the interior of the latter with 25 the end of the ascension pipe, the free extremity of the conduit being provided with a flange 3 cooperating with the flange F and suitably secured thereto. Preferably the conduit is curved or inclined downwardly 30 from its point of connection with the ascension pipe to the point where it merges into the valve casing so that at the latter point the upper interior surface of the conduit is in substantial horizontal alignment 35 with the lower interior surface thereof adjacent the flange 3. The conduit may be provided with suitably positioned spooning holes 4, 4 for permitting inspection of its interior or the introduction of scraping tools 40 or the like if desired; these holes may be provided with removable covers 5 of any suitable type.

The valve casing 1 embodies a preferably 45 integral depending skirt or flange 6 adapted for connection to the top of the collector main C and is open at its upper end so as to permit access to its interior. For closing the upper end of the casing a cover 7 is provided and is preferably secured to an 50 arm 8 hinged to a bracket 9 on the side of the casing and conveniently provided with a substantially vertically extending member 10 having a hooked extremity to afford a convenient means of raising and lowering 55 the cover about the pivot.

Disposed within and rising above the floor or bottom 11 of the casing is an annular dam or ring 12 which is preferably arranged in axial alignment with the skirt 6, and may 60 extend thereinto for a short distance. This dam is preferably cast integral with the valve casing and supported by a narrow web 13 which forms part of the casing floor, the plane of which is somewhat below the 65 level of the interior of the conduit at its

point of juncture with the valve casing, whereby a moat 14 is formed at the bottom of the latter and bounded on its inner side by the dam, which, in turn, bounds the outlet from the casing.

70

The floor of the casing on the side of the latter opposite to that to which the conduit is connected is extended outwardly as at 11' beyond the line on the skirt to form the bottom of an offset pocket 15 in the lower part 75 of the casing and through this pocket is horizontally extended a valve clapper shaft 16 upon which is mounted the valve clapper 17. The latter comprises a circular, preferably upwardly domed central portion of 80 slightly greater diameter than the dam 12 from which depends a narrow peripheral flange 17' carrying a plurality of spaced feet or lugs 18. The clapper also comprises a pair of laterally spaced outwardly extending arms 19 which project beyond the periphery of the central portion of the clapper and terminate in bosses 20 provided with squared holes 21 for the passage of the valve clapper shaft 16 which is correspondingly squared throughout the portion thereof which extends through the pocket 15, as best shown in Fig. 4. The clapped shaft is journaled for rotation in the side walls of the pocket and may be provided with an adjustable gland 22 cooperative with packing 23 surrounding the shaft where it passes through one of said walls so as to prevent leakage about the shaft at that point, while the other end of the shaft beyond its squared portion is reduced in diameter and journaled directly in the adjacent wall. Conveniently the bore in which the last mentioned end of the shaft is disposed is continued through the wall and a boss 24 with which the latter is provided and internally threaded at its outer extremity for the reception of a removable plug 25 so that by taking out the latter the end of the shaft can be exposed to facilitate its removal by driving it out endwise.

100

Conveniently the feet 18 may be symmetrically disposed about the valve clapper preferably, when three are employed, so that one foot will be diametrically opposite 115 the shaft 16 and the other two on opposite sides of the clapper as best shown in Fig. 5, the height of the said feet being such that when the clapper is in closed position, as shown in full lines in Fig. 1, the feet will 120 rest on the bottom of the moat 14 so that a plurality of peripherally spaced vents 27, substantially in the form of elongated slots, are formed between the adjacent side edges of the several feet, the bottom of the moat 125 and the lower edge of the clapper, which latter is arranged to lie below the level of the upper edge of the dam 12.

130

Means are provided for conveniently effecting rotation of the clapper shaft 16.

from the exterior of the casing, said means preferably comprising an arm 30 connected at one end to the free end of the shaft which projects beyond the gland 22 and at its other 5 to a link 31 which extends substantially horizontally rearwardly to terminate more or less adjacent the upper end of the ascension pipe at which point the link is connected to a counterweight lever 32. This 10 lever may be preferably provided with three arms extending in different directions from a central web which is pivoted on a horizontally disposed pivot pin 33 mounted in a bracket 34 in turn secured to 15 an angle iron 35 extending along the front of the ascension pipes and supported therefrom. This constitutes a convenient manner of mounting the bracket but any other suitable method of so doing may be employed if desired. The counterweight lever, 20 which in Fig. 1 is shown in one position in dotted lines and in another position in dot and dash lines, is so arranged that one of its arms, 37, extends in a generally upward 25 direction from the pivot; to this arm, about midway between its ends, is connected the link 31 while at the outer end of the arm is disposed a counterweight 38. The other two arms 39 and 40 of the lever are 30 respectively arranged to extend more or less rearwardly and more or less downwardly from the central web and may be conveniently provided at their extremities with hooks for the reception of chains or the like 35 (not shown) to enable the lever to be rotated about its pivot from a point remote therefrom.

The several parts to which reference has just been made are so arranged and proportioned that when the valve clapper is 40 in closed position, as shown in full lines in Fig. 1, the link 31 is projected rearwardly so that the arm 37 of the counterweight lever is disposed in the rear of the vertical plane passing through the axis of the pivot 45 38, while when the valve clapper is in open position, as shown in dot and dash lines in said figure, the link will be projected forwardly and the lever arm swung to a position 50 on the opposite side of and in front of said plane so that the counterweight will operate to hold the valve in such open position. Thus by pulling on either of the hooked arms 39 or 40 of the counterweight 55 lever the valve clapper may be readily opened or closed by the exercise of a relatively small amount of force since as soon as the counterweight is moved over center in its passage from one limit position to 60 the other it thereafter assists in the movement of the valve and upon reaching the end of its path of movement in either direction operates to hold the valve clapper in either open or closed position. It will be 65 apparent that by reason of the arrange-

ment and location of the counterweight lever the latter may be conveniently operated to actuate the valve from a plurality of different points, such, for example, as the charging lorry (not shown) in the rear 70 of the ascension pipe or from the collector main walk W or from the top of the furnace as may be desired, thus facilitating the operation of the furnace and reducing the labor requisite therefor. 75

For the purpose of thoroughly flushing the interior of the valve casing and conduit with a suitable flushing liquid so as to effect the removal of carbon deposits as required, we prefer to provide a plurality of 80 spray nozzles through which said liquid may be introduced, one of nozzles 42 being disposed to direct the fluid angularly downward onto the valve clapper and adjacent parts and another of said nozzles 43 being 85 arranged to direct the fluid more or less horizontally through the lower part of the conduit in the direction of the valve clapper. To this end the valve casing may be provided at its forward side with an angularly disposed boss 42' suitably bored and threaded for the reception of the nozzle 42 and with another substantially horizontally extending boss 43' disposed on the lower side of the conduit and suitably bored and 90 threaded for the reception of the nozzle 43. Thus the fluid issuing from the nozzle 42 is effective to thoroughly clean the upper surface of the valve clapper and its adjacent parts while that issuing from the nozzle 43 will impinge on the interior of 95 the forward side of the valve casing and also against the lower face of the valve clapper when the latter is in raised position. 100

With the parts constructed and assembled substantially in the manner which we have illustrated and described, it will be apparent that the gases ascending from the furnace through the ascension pipe will be directed 110 into the interior of the valve casing and there passes to the collector main thereafter controlled in conformity with the position of the valve clapper 17 and that by suitable actuation of the counterweight lever the 115 valve clapper may be moved from open to closed position or vice versa when desired. It will be further apparent that the flushing liquid after it is injected into the interior of the valve casing through the nozzles 42 and 120 43 will flow by gravity into the moat 14, irrespective of the position of the valve clapper, and collect therein until it attains a sufficient depth to overflow the upper edge of the dam 12 and pass to the collector main. Thus, when the clapper is in closed position with the feet 18 resting on the bottom of the moat, the lower edge 125 of the clapper as well as the feet are continuously immersed in the liquid, thereby 130

forming an effective liquid seal against the passage of the gases while any excess of the flushing liquid beyond the amount required to keep the moat full can continuously escape from the interior of the casing through the vents 27 and over the edge of the dam 12 thus preventing, under normal conditions, the accumulation of an undesirable quantity of said liquid in the bottom 10 of the valve casing and in the conduit. However, should such accumulation take place owing to the introduction of a greater quantity of flushing liquid than can vent itself through the vents 27 or owing 15 to the accidental clogging of the vents, the accumulated liquid cannot overflow into the ascension pipe and thence to the furnace until the level thereof in the valve casing and conduit has attained a point sufficient 20 to allow the fluid to pass the elevated mouth of the conduit adjacent the flange 3, a condition which is extremely unlikely to occur under practical conditions of operation.

25 While we have herein illustrated and described a preferred embodiment of our invention with considerable particularity and have shown the same in operative association with a by-product coke furnace, we do not 30 thereby desire or intend to confine the use of the invention solely thereto as it may be employed with equal facility in association with other types of furnaces, retorts and the like, nor do we intend to thereby limit ourselves to the precise embodiment of the 35 invention to which we have referred as the design, arrangement and construction of the various elements thereof may be modified in numerous particulars if desired without departing from the spirit and scope of the 40 invention as defined in the appended claims.

Having thus described our invention, we 45 claim and desire to protect by Letters Patent of the United States:

50 1. A device of the class described comprising a casing having an outlet, a valve clapper in the casing adapted to be closed over said outlet, means for admitting liquid to the casing, and means for permitting a portion of said liquid to escape into said outlet while said clapper is closed thereover.

55 2. A device of the class described comprising a casing having an outlet, a valve clapper adapted to close over the outlet in the casing, means for admitting liquid to the interior of the casing, and means adapted to receive and retain a portion of said liquid and to permit the balance thereof to escape beneath said clapper and into said outlet while said clapper is closed thereover, said retained portion of said liquid, in co-operation with said clapper, forming a seal against the passage of gas from the interior 60 of the casing to the outlet.

65 3. A device of the class described com-

prising a casing having an outlet, an annular dam surrounding the outlet and extending above the floor of the casing, a valve clapper operative to close over the upper edge of said dam, means for admitting liquid 70 to the casing to a predetermined depth sufficient to immerse the edge of said clapper whereby a liquid seal is formed against the passage of the gas through said outlet when the clapper is closed thereover and 75 means adapted to permit the escape beneath said clapper and into said outlet of any liquid in excess of that required to form said seal.

4. A device of the class described comprising a casing having an outlet, an annular dam surrounding said outlet and extending above the floor of the casing, means for admitting liquid to the interior of the casing to surround said dam therewith, a 80 valve clapper disposed within said casing, relatively movable with respect thereto and operative to close over the upper edge of said dam and extend below said edge and into said liquid whereby a liquid seal is 85 formed against the passage of gas from the interior of the casing to said outlet and means adapted to permit the escape beneath said clapper and into said outlet of any liquid admitted to the casing in excess of 90 that required to form said seal.

5. A device of the class described comprising a casing having an outlet, an annular dam surrounding said outlet and extending above the floor of the casing, a 100 movable valve clapper disposed in the casing and adapted to close over the outlet and overhang the dam, said clapper having a plurality of spaced feet depending from its lower edge adapted to rest on the floor of 105 the casing when the clapper is in said closed position.

6. A device of the class described comprising a casing having an outlet, an annular dam surrounding the outlet and rising 110 above the floor of the casing, a valve clapper positioned in the casing and adapted to be closed over said outlet or moved to a position to afford a free passage through the outlet, the clapper being provided with a 115 plurality of spaced feet depending from its edge and adapted to rest on the floor of the casing when the clapper is closed over the outlet whereby a plurality of vents are afforded through which liquid accumulated 120 in the bottom of the casing may escape beneath the edge of the clapper and over the edge of said dam into said outlet.

7. A device of the class described comprising a valve casing having an outlet, an 125 inlet conduit extending from the casing and having its inlet end at a higher level than its outlet end, a valve clapper in the casing adapted to be closed over said outlet, means for admitting liquid to the casing, and means 130

for permitting a portion of said liquid to escape into said outlet when said clapper is closed thereover.

8. A device of the class described comprising a casing, an inlet conduit extending from said casing and having its inlet end disposed at a greater height with respect to the casing than the end which communicates therewith, an outlet in the bottom of the casing, an annular dam surrounding said outlet and rising above the floor of the casing, a valve clapper movably disposed within the casing and adapted to close over said dam and extend below the upper edge thereof, means for directing flushing liquid into the casing in a plurality of different directions, and means for permitting the escape of a portion of said fluid beneath the valve clapper and into said outlet when the clapper is closed thereover.

9. A device of the class described comprising a valve casing provided with an outlet and an inlet conduit extending from the casing and having its inlet end disposed at a higher level than its outlet end, a valve clapper adapted to close over said casing outlet, means for admitting flushing liquid to the interior of the casing in a substantially horizontal direction, means for admitting flushing liquid to the casing in a direction to impinge on the top of the clapper when closed over the outlet, and means adapted to receive and retain a portion of said liquid and to permit the balance to escape into said outlet when said clapper is closed thereover, said retained portion of said liquid in cooperation with said clapper forming a seal against the passage of gas from the interior of the casing to the outlet.

In witness whereof, we have hereunto set our hands this 24th day of September, 1925.

HERBERT C. WILLIAMSON.
BUFORD M. STUBBLEFIELD.
